Primary Examiner — Cynthia R Underwood(74) *Attorney, Agent, or Firm* — Richards Patent Law P.C.(57) **CLAIM**

The ornamental design for a cord management device, as shown and described.

DESCRIPTION

FIG. 1 is an isometric view of a cord management device showing my new design;

FIG. 2 is an inverted isometric view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

1 Claim, 6 Drawing Sheets(56)
